UNITED STATES PATENT OFFICE

KURT THEODORE POTTHOFF, OF BROOKLYN, NEW YORK, ASSIGNOR TO U. S. GALVANIZING & PLATING EQUIPMENT CORPORATION, A CORPORATION OF NEW YORK

APPARATUS FOR TREATING MATERIAL

Application filed June 8, 1927. Serial No. 197,414.

This invention relates to machines for treating articles in a liquid such for instance as a cleaning or pickling solution for small articles or any other liquid treatment for 5 coating said articles.

Such small articles as knives, forks, spoons and the like require very careful and uniform treatment in the liquid and when handled in a mass have a tendency to stick together 10 or to become wedged into parts of the treating or conveying mechanism so that the articles are liable to become spotted or bent. In the prior treatment of such articles much hand labor has been involved and the 15 machines used have been objectionable in their failure to properly stir and tumble and mix the articles to give the desired uniform treatment over all of the surfaces. It has also been difficult with prior mechanisms to have 20 free and open access to the articles at all times so that in case of jamming of any of the articles in any part of the apparatus, it has been necessary to detach portions of the mechanism to reach the inside.

25 To overcome these objections the apparatus of this invention provides a series of open top basket like containers which are moved or rocked to agitate and stir the material in the liquid and at predetermined intervals 30 these containers are shifted so as to transmit the load of material from one to the other and thus further stir and mix the material and break up any adhesion between the individual articles. Specifically certain of the 35 baskets are first rocked from receiving position to an upright or intermediate position and then back to the receiving position. This series of operations continues over a certain predetermined period until finally the 40 basket is brought to its intermediate position and from there bodily raised to discharge its contents into a second basket which is in a receiving position. The first basket is then lowered to its intermediate position after 45 which its cycle of operation will be repeated while the second basket is rocked from and to its receiving position in the same manner as previously described in connection with 50 the other basket. Finally the second basket

is brought to its discharging position. This series of steps may continue as desired.

It is a further object of my invention to provide mechanism to actuate the baskets and to provide mechanism for discharging 55 the contents of one basket into the other basket. While these baskets may take various forms, it is a further object of my invention to so construct the same that they 60 may be readily inspected. While I have in one specific embodiment of my invention shown a series of these baskets mounted parallel to each other, it will, of course, be understood that one or any number might 65 be used.

It is a further object of my invention to utilize the baskets in a plurality of sections whereby the baskets in the first section, which baskets are disposed in a suitable solution, can effect a cleaning action of the articles 70 disposed therein. The second section might contain suitable solutions, such as acids or the like. More specifically the first section is made up of a loading basket, a series of cleaning baskets, and finally, what might be 75 termed, transferring baskets. With the exception of the transferring baskets each basket consists of a single basket-shaped member having a partition intermediate its ends to form two article receiving compartments. As will be clear from the disclosure the baskets may comprise a single compartment or a multiplicity thereof and the operation of the various baskets controlled 80 accordingly. The loading basket compartments receive the articles alternately and alternately discharge the same into the first cleaning or receiving basket. This latter basket is then actuated or rocked a certain number of times after which it is bodily 85 raised to discharge simultaneously its contents from both compartments into the second cleaning basket. The above cycle is then repeated for each cleaning basket until the transferring baskets are reached. The transferring baskets are mounted on separate aligned shafts and each is adapted to receive 90 the articles from one compartment of the cleaning baskets. Certain of the articles will 95 have then been subjected to the cleaning solution.

tion longer than other of the articles and to compensate for this difference, suitable mechanism is provided for rocking one of the transferring baskets in its solution a longer time than the other basket. The second section of baskets comprises a series of single baskets each having only a single compartment and similarly arranged to those in the first section. This single basket arrangement is permitted for the reason that the articles are passed through the solutions into which the second section baskets are disposed, twice as fast as through the solution of the first section. The transferring baskets are so timed that they will discharge their contents alternately into the second section baskets. It will thus be seen that the transferring baskets perform in addition to the compensating function, the function of feeding the articles from a parallel line into a single line.

It is an object of my invention to accomplish the above results in a very simple and efficient manner considering the several functions to be performed.

It is desirable to be able to change the length of time for subjecting the articles to certain solutions and it is an object of my invention to provide improved means for accomplishing this result. It is a further object to provide means whereby this time interval may not be changed without first stopping the machine. Another object is to provide in combination with the first and second sections, a drying mechanism which has baskets or suitable receptacles operated in timed relation to the other baskets, thereby receiving the articles from each basket and keeping the same separated.

With the foregoing and other objects in view my invention consists of certain other novel features of construction and arrangement of parts which will be apparent from the disclosure hereinafter more fully described and shown by the accompanying drawings wherein

Fig. 1 is a perspective of the first and second sections.

Fig. 2 is a side elevation of the first section.

Fig. 3 is a side elevation of the second section and a part of the first section.

Fig. 4 is a plan view of the first section and a fragment of the second section.

Fig. 5 is a plan view of the second section with parts of the drying mechanism and the second section attached.

Fig. 6 is a plan view of the drying mechanism.

Fig. 7 is a side elevation of the drying mechanism.

Fig. 8 is a side elevation of a pair of the baskets in the first section and shown in their intermediate position.

Fig. 9 is a view similar to Fig. 8 showing the baskets in a receiving position.

Fig. 10 is a view of the baskets shown in Fig. 8 in their cooperating, discharging and receiving positions.

Fig. 11 is a vertical transverse section taken substantially on the line 11-11 of Fig. 8, and showing the clutch mechanism and cam control therefor which is adapted to control the discharging position of the baskets.

Fig. 12 is a view similar to Fig. 11 showing the clutch engaged.

Fig. 13 is a fragmentary side elevation of the machine adjacent the transferring baskets.

Fig. 14 is a vertical transverse section taken substantially on the line 14-14 of Fig. 13.

Fig. 15 is a plan view of Fig. 14.

Fig. 16 is a side elevation of a part of the second section adjacent the first section and taken substantially on line 16-16 of Figs. 5 and 18.

Fig. 17 is a continuation of the right hand end of Fig. 16.

Fig. 18 is a vertical transverse section taken substantially on the line 18-18 of Figs. 13 and 16.

Fig. 19 is a plan view of the mechanism for varying the time interval of submersion of one basket in its solution.

Fig. 20 is a side elevation thereof.

Fig. 21 is a transverse section on line 21-21 of Figs. 19 and 20.

Fig. 22 is a developed view of the shifting cam for the controlling mechanism shown in Figs. 19 and 21.

Fig. 23 is a diagram showing the relative positions between the cam for bringing the baskets to their discharging position and the various positions of the baskets.

The first section comprises a frame having I-beam side members 2 mounted upon a series of standards 3. Disposed below the frame and intermediate the sides is a tank 4 which has an open top and may be made of any material suitable for the liquid to be contained therein. As shown in Fig. 4 this tank terminates at 5 and 6 while the side walls 7 thereof are spaced inwardly from the side members 2.

The top 8 is disposed below the sides 2 to permit a series of baskets to be suitably carried by the side members 2. A loading basket 9 has an arcuate bottom and end members 10 and 11 intermediate of which is a partition 12. A suitable deflecting means mounted on the front end 13 may be used and which will be described later in connection with other of the baskets. The loading basket is immovably secured to a transverse shaft 14 which in turn is immovably secured to a pair of lifting arms 15 disposed at each end of the basket 9. The arms 15 are secured to a transverse shaft 16 which in turn is

carried by the sides 2 in journals 17. The means for actuating the loading basket will be described later in connection with the remaining baskets of the first section which comprise a series of identical baskets 20, 21, 22 and 23 and a pair of transferring baskets 24L and 24R. While four baskets have been shown intermediate the loading basket and transferring baskets, it will be understood that any desired number may be used or that the same may be of any width suitable. Each of the baskets 20 to 23 has, as shown in Fig. 8, a substantially flat bottom portion 25 terminating in a rearward portion 26 and an upwardly extending portion 27. The bottom 25 may be made of any suitable perforated material to allow the solution to drain from the basket when it is raised to discharging position. The portion 27 carries, if desired, a removable discharge chute 28 which tapers toward its outer end. All of the baskets including the loading basket may be provided with a discharge chute 28 although under certain circumstances such may not be necessary. Each of the baskets 20 to 23 is secured to a shaft 29 extending across the top thereof. The outer ends of the shafts are journaled in lifting arms 15. The other ends of the lifting arms are journaled upon transverse shafts 30 disposed normally in front of each basket.

It will be noted that each of the baskets 20 to 23 is provided with a partition 31 in alignment with the partition 12. The rocking mechanism for the baskets 20 to 23 is identical for each basket and the description of one will suffice for all. This mechanism comprises a reciprocable rod 34 disposed along one of the side members 2. This rod is reciprocated by suitable mechanism to be later described. Journaled upon the shaft 30 is an arm 35 the outer end of which is pivotally secured as at 36 to the rod 34. Projecting rearwardly from the arms 35 is a bearing lug 37 to which is pivotally secured at 38 a connecting link 39, the outer end of which is pivotally connected as at 40 to a crank arm 41. The crank arm 41 is secured to an outer end of the shaft 29. It will thus be seen that upon reciprocation of the rod 34, the basket will be oscillated or rocked from its intermediate position as shown in Fig. 8 to its receiving position as shown in Fig. 9 and vice versa. During this movement the arms 15 are stationary and the shafts 29 rest in suitable supports 42, which as shown in Fig. 10 are mounted on the top of each of the sides of the tank 4. It will be understood that material of one particular kind, say spoons, will be transferred from compartment 9L of the loading basket 9 to the compartment 20L of the basket 20 when the latter is in its receiving position as is shown in Fig. 9. The loading basket 9 will thereafter be returned to receive another load of ma-

terial during which time the basket 20 will be rocked a predetermined number of times. During rocking of the basket 20 the compartment 9R will be loaded. The loading basket will again be raised to discharge its contents into the compartment 20R when the basket 20 is again in a receiving position. When the compartment 20R is loaded the basket 20 will again be oscillated a predetermined number of times, after which the basket 20 will be bodily raised to discharge its contents into the compartments 21R and 21L of the basket 21 as shown in Fig. 10. Due to the alternate feeding of the material, first to the compartment 20L and then to the compartment 20R, and the simultaneous discharge from both compartments, the contents in the compartment 20L will be subjected to the solution within the tank 4 a greater length of time than the contents of the compartment 20R. This inequality, however, is compensated for by the transferring baskets to be described later. In the machine herein disclosed the timing of the loading basket 9 and the basket 20 is such that the contents of the compartments 20L and 20R are subjected to the cleaning liquid one minute and two minutes respectively. The contents in the compartments of the basket 21 will, of course, be subjected to the cleaning liquid the same length of time, namely two minutes, after which the basket 20 will be bodily raised to discharge its contents into the basket 22 and so on to the basket 23. Each basket is, however, rocked in the cleaning solution the same length of time.

The mechanism for bodily raising the baskets at predetermined intervals includes clutch mechanism for securing each of the lifting arms to the arms 35 of the rocking mechanism. The loading basket is not oscillated and for that reason no linkages similar to the links 39 and 41 are used. The loading basket 9 is merely bodily raised to its discharging position by mechanism which is identical to the mechanism for connecting the arms 15 of the other baskets to the arms 35. The description of the mechanism for the basket 20 will suffice for all. The hub of the arm 35 carries parallel clutch pins 43 receivable in a groove 44 formed in the side of a slid able collar 45 which is splined to the shaft 30. To actuate the collar 45 a cam shaft 50, as shown in Fig. 2, is disposed along one side of the machine and journaled in the standards 3. A cam 51₂₀ is secured to the shaft and has a cam groove 52 in one side thereof. A raised portion 53 of the groove is adapted to engage a roller 54 which is carried upon a collar actuating arm 55. This arm is journaled in a suitable bracket as at 56 while its upper end is forked and pivotally secured to a ring 57 receivable in a suitable groove in the collar 45. Rotation of the cam 51₂₀ causes engagement of the portion 53

with roller 54 and the collar 45 is brought into operative engagement with the pins 43. The cams for the respective baskets are given a prime number which is the same as the basket associated therewith. The cams are so timed that clutch engagement is brought about when the rod 34 is in the position shown in Fig. 9. To bring one basket to its discharging position while the others are in their receiving position, it is necessary that the cams be so timed or angularly disposed about the shaft 50 that the clutch mechanism, say for the basket 20, will be in engagement while the clutch mechanisms for the remaining baskets will be out of engagement. When the clutch mechanism for basket 20 is made operative so as to raise the arms 15 disposed on each side of the basket 20, the arm 35 will be positively connected to the shaft 30 as through the pins 43 and collar 45 which is splined to the shaft 30. The cam is also timed so that clutch engagement is effected when the rod 34 is in the position shown in Fig. 9. During this position the basket 20 will be in its intermediate position, due to the linkages 39 and 41, but upon movement of the rod 34 in a right hand direction the basket will be bodily raised to a position shown in Fig. 10. Remembering that the clutch mechanisms for the remaining baskets are not in engagement upon movement of the rod 34 in the right hand direction, the linkages 39 and 41 for the remaining baskets, such as 21, will cause the same to be swung to their receiving position as shown in Fig. 10. The chute 28 of the basket 20 will then properly discharge the contents from the compartments 20L and 20R to the compartments 21L and 21R. The contents of the basket 20 will have been discharged by the time rod 34 moves again in the left hand direction. By the time the shaft 29 is again supported by the supports 42 the cam 51₂₀ will have caused disengagement of the clutch mechanism and accordingly thereafter permit the arm 35 to merely have rotatable connection with the shaft 30 thereby leaving the arm 15, which is secured to the shaft 30, remain stationary. Upon the next right hand movement of the shaft 34 the linkages 39 and 41 will rotate the basket 20, in a counterclockwise direction, to its receiving position as shown in Fig. 9, whereupon the compartments 20L and 20R may again be filled as before described. After the basket 21 has been filled, it will be rocked a predetermined number of times before the clutch mechanism for controlling the discharge of the basket 21 will be made operative by a cam 51₂₁. When actuation of the clutch mechanism does occur the basket 22 will be in a receiving position so that with the relation between the baskets 21 and 22 will be similar to the relation between the baskets 20 and 21 shown in Fig. 10. This series of operations of each basket first receiving its material,

then rocking the same a predetermined number of times and then being raised to discharge its contents into the succeeding basket will be continued until the transferring baskets 24L and 24R are reached.

The mechanism for rocking and raising the transferring baskets is broadly identical to the mechanisms for the other baskets with a few minor changes which will be noted. A shaft 60 is supported by suitable journals carried by the frames 2 and by an intermediate bracket 61 supported on a cross member 62 which joins the side frames 2. Sleeves 63 and 64 are journaled upon the shaft 60 at each side of the support 61. Collars 60' are secured to the shaft 60 to hold the sleeves 63 and 64 in position. Inner lifting arms 65 are secured to the inner ends of the sleeves 63 and 64 while lifting arms 66 are secured to the outer ends of the sleeves 63 and 64. The free ends of the arms 65 and 66 rotatably carry shafts 67 and 68. Secured to the shafts 67 and 68 respectively are the baskets 24R and 24L, it being noted that the latter are approximately the width of the compartments of the basket 23. The baskets are shaped generally the same as the baskets 20-23, and may be provided with a chute 28' approximately one-half the width of the chute 28. The chutes 28' will have their outer sides tapered inwardly to a greater extent possibly than the chutes 28 for the purpose of deflecting the material to a more central position where it will be discharged into the second section of baskets. In this latter section the baskets are disposed in a central position and are not provided with two compartments. The outer end of the shafts 67 and 68 are also supported by the supports 42, the inner ends being supported only by the arms 66. Secured to the shaft 60 adjacent one of the side frames 2 is an actuating arm 67', which as shown in Fig. 14, has bearing lugs 68' and 69 on both sides thereof while the outer end of the arm is pivotally connected to the end of the rod 34. Links 39 and 41, identical to the links connected to the arms 35 for rocking the baskets 21 and 22 operatively connect the lug 69 and basket shaft 67. Mechanism for reciprocating the rod 34 is connected to the arm 67' as by a link 70 which in turn is connected to a suitable crank to be described later. To rock the basket 24L independently of the basket 24R, there is secured to the other end of the shaft 60 a short arm 71 which is connected to a link 72 in turn pivotally secured to a crank arm mounted upon the outer end of the shaft 68, said arm being identical to the arms 41. The point of pivotal connection between the link 72 and arm 71 is in alignment with the axis of the bearing lug 69 so that the same degree of motion will be imparted to both baskets 24L and 24R. It will thus be seen that during continued reciprocation of

the rod 34 as by the link 70 the shaft 60 will be oscillated and accordingly impart a rocking motion to the baskets 24R and 24L.

As before stated the loading basket 9 discharges alternately to the left and right hand compartments of the basket 20 and in order to compensate for the short length of time that the contents in the compartment 20L will have been subjected to the solution in tank 4, the basket 24L is made to rock two minutes whereas the basket 24R rocks only one minute before said baskets are raised to their discharging position. This will thereby cause the articles being cleaned to have been subjected an equal length of time to the solution within the tank 4. Due to the fact that the baskets 24L and 24R are filled simultaneously from the basket 23, it will be seen that the basket 24R will discharge its contents one minute before the basket 24L discharges its contents. To accomplish this a clutch collar 75 is splined to the shaft 60 and adapted to engage clutch pins 76 which are carried by the hub of the arm 66. This clutch mechanism is disposed between the end of the sleeve 63 and the frame 2 and is actuated by an arm 77 pivotally supported at one end by a shaft 56 while its other end is pivotally connected to a link 79 which in turn is connected to a clutch shipper mechanism 80. As shown in Fig. 14 the arm 77 carries a roller 81 receivable in a cam groove 82 formed in the face of a cam plate 83 which is secured to the shaft 50. This cam plate is identical in construction to the cam 51₂₀ but is angularly disposed relative to the other cams to obtain proper timed operation of the clutch 75. In order to actuate the basket 24L a clutch mechanism 85 is disposed between the right hand end of the sleeve 64 and the adjacent side frame 2. This clutch mechanism also includes pins 76 and a shipper mechanism 86. The latter is operated by a lever 87 pivoted upon the cross frame 62. A depending arm 88 is connected to an arm 89 carried upon a hub 90, as by a connecting rod 91. The hub 90, like the arm 77, is journaled upon the shaft 56 which is supported by the standards 3 as shown in Fig. 9. Secured to the other end of the hub 90 is a short arm 93 which carries out at its outer end a roller 94. This roller is receivable in a cam groove 95 formed in the side of a cam plate 95 which is also secured to the shaft 50. The plates 83 and 95 are relatively angularly disposed so that the clutch 75 will be thrown into engagement prior to engagement of the clutch 85, thereby lifting the basket 24R approximately one minute prior to the lifting of the basket 24L. It will thus be seen that the baskets 24L and 24R discharge alternately into a basket of the second section.

The second section comprises a frame having sides 100 which, as shown in Fig. 5, are disposed inwardly from the sides 2 of the

first section frame. This is for the reason that the baskets in the second section are approximately one-half as wide as the baskets in the first section. The sides 100 are supported by standards 101. A series of separate tanks 101', 102, 103 and 104 are disposed between the sides 100, while a series of baskets 105, 106, 107 and 108 are adapted to submerge their contents within any suitable solutions contained within the respective tanks. It is desired to pass the articles through the second section at a greater rate than through the first section, and to accomplish this the second section baskets are operated at a greater rate than the baskets of the first section. Also certain of the baskets of the second section are operated at a different rate. Due to this latter condition, the second section baskets are operated by a different combination of linkages than are the baskets of the first section. The baskets of the second section and their operating mechanism are best shown in Figs. 16 and 17, the latter being a continuation of the right hand end of Fig. 16. As shown in Fig. 5, the basket 105 is secured to a transverse shaft 111 which is rotatably supported by journals 112 carried on the side frames 100. The shaft 109 is also adapted to rest in supports 42 which are carried on the top of the sides of the tank 101'. An arm 113 is secured to one end of the shaft 109 and a link 114 is pivotally connected to the arm 113 as at 115. The inner end of the link 114 is pivotally connected as at 116 to an arm 117 which projects outwardly from the hub 118. This hub is journaled upon the shaft 111 and carries clutch pins similar to the clutch pins 43 shown in the clutch in Fig. 11. Projecting downwardly and forwardly from the hub 118 is a long arm 119 to the outer end of which a rod 121 is pivotally connected as at 120.

Mechanism for oscillating the arm 119 includes a link 122 which is pivotally connected as at 123 to the arm 119. Cooperating with the clutch hub 118 is a shiftable clutch collar 124. This collar is actuated by a forked end 125 of a lever 126 which is pivotally supported upon a shaft 127. The shaft 127 serves the same purpose as the shaft 56 and is supported by bracket arms 128 depending from the standards 101. The arm 126 carries a cam roller 129 which is receivable in a cam groove in the face of the cam plate 130. The cam plate 130 is secured to a shaft 131 which is rotatably supported by brackets 128. These brackets are secured to the standard 101 similar to the manner of supporting the shaft 50 by the standards 3. The rod 121, as seen from combined Figs. 16 and 17 extends past the baskets 106 and 107 without connection thereto in any way, and is finally pivotally connected as at 135 to a rocking arm 136. This arm has a hub journaled upon a shaft 137 and with which is associated

clutch mechanism identical to the clutch mechanism associated with the arm 119. With the exception of the pivot lug 123, the arm 136 is identical in all respects to the arm 119. The arm 136 has an arm 138 to which is operatively connected rocking links 113 and 114. The basket 108 is secured to a shaft 139 which is pivotally supported at its outer ends by lifting arms 140. The shaft 139, like the other basket shafts, is removably supported by supports 42. The clutch mechanism for the arm 136 is actuated by a forked arm 141 which is pivotally mounted upon the shaft 127 and carries a cam roller 142. A cam plate 143 secured to the cam shaft 131 has a cam groove to receive the roller 142. This cam plate is identical to the other cam plates. It will thus be seen that the baskets 105 and 108 can be given a rocking motion in addition to being lifted to their discharging position.

The intermediate baskets 106 and 107 (Figs. 16 and 17) are actuated by common linkages although the basket 106 does not have any rocking motion. Instead, as soon as articles are discharged into basket 106 the same is lifted substantially immediately to its discharging position although the basket 107 has rocking motion in addition to its discharging motion. To accomplish these results, the basket 106 is secured to a transverse shaft 150 which is journalled in the free ends of lifting arms 151. The inner ends of the lifting arms are secured to a transverse shaft 152 which is supported by the side frames 100 as in journals 153. The shaft 150 is also removably supported in supports 42. A member having a hub 154 rotatably mounted on the shaft 152 has arms 155 and 156 extending the opposite directions. The arm 155 is pivotally connected to a link 157 which is actuated by suitable mechanism to be described later. The arm 156 is pivotally connected to a reciprocating rod 158. The hub 154 has a clutch mechanism associated therewith identical to the clutch mechanisms associated with the shafts of the other baskets. This clutch mechanism is controlled by a cam plate 159 cooperating with a roller 160 which is carried upon a clutch-shipping arm 161, the arm 161 being pivotally mounted upon the shaft 127. Certain other details of construction are embodied in the cam mechanism 159 for the purpose of varying the length of time of submersion in the liquid of the articles carried by the basket 106. This mechanism will be described later. In order to turn positively the basket 106 completely over as shown in the dotted line position in Fig. 16, a bracket 162 secured to the inner side of the right hand frame 100 pivotally supports one end of a link 163 while the other end of this link is pivotally connected as at 164 to an arm 165 which is secured to the shaft 150. During

raising of the arms 150 the basket 106 will be turned relative to the arms 150 in a clockwise direction due to the arm 165, link 163 and stationary support 162.

The other end of the rod 158 is pivotally connected as at 165 to an arm 166. This arm is journalled upon a shaft 167 which is carried in suitable journals 168 supported by the frame 100 and has associated therewith clutch mechanism similar to the clutch mechanisms for the other baskets. A cam plate 169 secured upon the shaft 131 cooperates with a cam roller 170 which is carried on a clutch-actuating arm 171. The arm 171 is also journalled on the shaft 127. The arm 166 carries a bearing lug 172 to which is pivotally connected a rocking link 173. An arm 174 pivotally connected to one end of the link 173 is secured to a shaft 175 which carries the basket 107. This shaft is journalled in the free outer end of lifting arms 176. The shaft 175 is also removably supported by supports 42.

The actuating mechanism for the cam shafts 50 and 131 and the links 70, 114 and 157 is disposed at one side of the adjacent ends of the two sections. This mechanism is generally indicated by 190 and comprises, as best shown in Figs. 13, 16 and 18, a casing 191 having laterally extending supporting portions 192 and 193 disposed on the top of the frame members 2 and 100. This casing, in addition to forming a housing for the several gears to be described, also provides suitable journals for the gear shafts. A longitudinal shaft 194, extending beyond the side of the casing, has secured thereto a driving pulley 195, while an idler pulley 196 is freely rotatable thereon. A worm 197 secured to the shaft 194 meshes with a worm gear 198 which is secured to a transverse shaft 199. The shaft 199 is suitably journalled in the casing 191 and carries a worm 200 and a pinion 201. A longitudinal shaft 202 carries a worm gear 203 meshing with the worm 200 and a sprocket 204. To drive the cam shaft 50 a chain 205 runs on the sprocket 204 and on a sprocket 206 which is secured to the shaft 50. The sprockets 206 and 204 are of the same diameter. To drive the cam shaft 131 at twice the speed of the cam shaft 50, a sprocket 207 is secured to the shaft 50, while a sprocket 208 is secured to the shaft 131, the sprocket 208 being one-half the diameter of the sprocket 207. A chain 209 connects the sprockets, and as shown in Fig. 5 the chain 209 extends laterally of the frames 2 and 100. The mechanism for actuating the link 157 comprises a shaft 210 carrying a gear 211 which is driven by the pinion 201 as through an intermediate or idler gear 212, all of which are suitably supported by the casing 191. A crank arm 213 secured to the shaft 210 is pivotally connected as at 214 to the link 157. To actuate the link 70 and accordingly recipro-

cate the rod 34, a gear 215 secured to a shaft 216 meshes with the pinion 201. A crank pin 217 carried by the gear 215 has pivotal connection with one end of the link 70. To actuate the link 122 and accordingly reciprocate the rod 121, a shaft 216, which extends to the right hand side of the standard 101, as best shown in Fig. 18, has secured thereto a hub 218 from which projects a crank arm 219. This arm is pivotally connected as at 220 to the link 122. It will of course be understood that the several gears included in the actuating mechanism 190 are properly proportioned so as to effect correct timing between the various actuating mechanisms for the baskets. In the specific embodiment of the invention, the ratio between the gears 203 and 215 is 1 to 6, between the sprockets 204 and 206, it is 1 to 1, and between the sprockets 207 and 208, it is 2 to 1.

The mechanism for angularly rotating the cam plate 159 relative to the shaft 131 to vary the length of time of submersion of the basket 106 in its solution is best shown in Figs. 16 and 19 to 22. The cam plate 159 has a hub 230 slidably supported on a sleeve 231 which, in turn, is slidably but non-rotatably carried by the shaft 131, a key 232 preventing relative rotation. The cam plate 159 is held against longitudinal movement as by a ring 233 receivable in a groove 234 formed in the hub 230. The ring 233 is carried by an arm 235 which is supported on the shaft 127. An angularly disposed cam slot 236 formed on the inner end of the sleeve 231 receives a roller 237 which is journaled on a stud 238, this stud being threadedly secured in the hub 230. An actuating arm 239, pivotally supported as at 240 by the frame 100, is operatively connected to the other end of the sleeve 231 as by a usual shipping collar and yoke generally indicated at 241. The arm 239 is provided with a handle 242 and a lug 243. It will thus be seen that upon movement of the handle 242 the cam slot 236 will cause rotation of the cam plate 159 relative to the shaft 131, the cam plate being held against longitudinal movement by the collar 233. The degree of cam plate rotation may be varied according to various conditions encountered in actual practice, but in the specific embodiment of the invention the adjustment is such as to obtain a variation in the length of time of submersion of the basket 106 of ten seconds. Two intervals of submersion time of the basket 106 are thereby provided, namely 10 seconds and 20 seconds.

In order to allow shifting of the cam 59 only when the machine is stopped, there is provided a transversely movable pin 245 supported by a bracket 240 and receivable in one or the other of the holes 246 and 247 which are formed in the lug 243. The bracket 240 is carried by one of the frame members 100. A spring 248 normally tends to move the pin

245 out of the holes 246 and 247, while an arm 249 of a bell crank pivotally supported as at 250 on the frame 100 tends to hold the pin in the holes by suitable mechanism to be described. A link 251 pivotally connected as at 252 to the other arm 253 of the bell crank, is pivotally connected as at 254 to an arm 255. This arm is secured to a vertical shaft 256 which is journaled in a bracket having a vertical supporting portion 257. This bracket is secured to the web of the frame 100. An arm 258, secured to the upper end of the shaft 256 and above the support 257, extends over the top of the frame 100, as shown in Fig. 19, and has a slot 259 formed in its outer end. As the operation of the machine is dependent upon which pulley 195 or 196 a driving belt may be on, means are provided for controlling the mechanism just described by the position of the belt. To this end there is provided a parallel motion mechanism, comprising parallel links 260 and 261. The link 260 is pivotally supported as at 262 on the top of the frame 100 and immediately below the arm 158. A small pin 263 carried by the arm 260 projects upwardly therefrom into the slot 259. The link 261 carries a handle 264 and is shown in Fig. 19 as being in its working position. A belt-controlling link 265, pivotally connected as at 266 to the free ends of the links 260, 261, is provided with a pair of downwardly projecting belt-engaging pins 267 spaced a sufficient distance apart to allow a belt to pass therebetween.

In the operation of this controlling mechanism, if it is desired to change the position of the cam 159 the operator by swinging the handle 264 in a counter-clockwise direction will shift a belt, shown in dotted line between the pins 267, onto the idler pulley 196. At the same time, the arm 258, through the pin and slot arrangement 259 and 263, will be moved in a counter-clockwise direction, as shown in Fig. 19, to allow the arm 255 to move the arm 249 of the bell crank in an outward direction as through the link 251. The spring 248 will move the pin 245 from the hole 246, whereupon the handle 242 may be moved in a clockwise direction to rotate the cam 159 as by the cam slot 236 and the roller 237. When this has been accomplished, the pin 245 will be in alignment with the hole 247 and upon rotating the handle 264 in a clockwise direction to shift the belt onto the driving pulley, the pin 245 will be moved into the hole 247, thereby locking the handle 242 against further movement.

The description of the general operation of the machine will be given in conjunction with the description of the graphic representation of the basket and cam positions shown in Fig. 23. The layout of the graphic representation is as follows: The horizontal lines rep-

resent the degrees of rotation of the cam shafts 50 and 131. The relation between the position of each basket and its respective cam is shown by pairs of vertically extending lines, which pairs are given the letter G with a prime number the same as the number of the basket to which each pair of lines relates. An illustration of the interpretation of one pair of lines will in general suffice for all.

10 The lines G²⁰ include a cam line 51₂₀. The raised portion 53 of the cam is represented at 20_a. The position of the basket is shown by the basket line 20_b. Each basket line has associated therewith three vertical lines numbered R, I and D, which lines when touched by the basket line such as 20_b indicate respectively the receiving, intermediate and discharge positions of the basket. It will be noted that the line 20_b touches the line D only

15 once during the 360 degrees of rotation of the cam 51₂₀, while the line 20_b alternately touches the receiving and intermediate basket position lines R and I a number of times during each revolution of the cam 51₂₀. This would

20 indicate that while the cam shaft 52 is making one revolution the rod 34 is reciprocating a number of times, thereby rocking the basket through the linkages and arms 35, 39 and 41 and shaft 29. When the cam shaft has ro-

25 tated sufficiently to allow the raised cam portion 53 indicated by the line 20_a to cause engagement of the clutch 44 as through the arm 55, the lifting arms 15 will be connected to the arm 35 and accordingly cause the arms 15

30 to raise and lift the basket 20 therewith to its discharging position. This raised position of the basket 20 is clearly indicated by the line 20_b touching the line D at a point on the 330° line. As will be noted, the cams

35 51₂₀—51₂₁ and the cams 83 and 95 are identical in that there is only one raised cam portion. The raised portion of the cams 51₂₀—51₂₁ and 83 and 95 is given the number of its associated basket with the sub-letter

40 "a." The cams 95 and 83 also have a single raised cam portion, 24R^a and 24L^a respectively. The cam portions 20_a to 24L_a are relatively angularly disposed by 60° about the shaft 50. The cam 51_a has two raised portions 9^a

45 and 9^b.

In the second section, cams 130 and 142 have a single raised portion 105^a and 108^a. It will be noted that there are 720 degrees of cam rotation represented due to the fact that the cam shaft 131 rotates twice as fast as cam shaft 50. The cams 130 and 142 are identical to the cam 51, while the cams 159 and 160 have raised cam portions 106^a and

50 107^a which are slightly shorter than the raised portions of the other cams. The cam 159 and the basket motion line associated therewith is shown in two positions which are obtained by actuating the hand lever 242.

55 Assuming the basket 9 to be in a receiving

position, the operator fills the compartment 9L with, say one kind of articles, such as spoons. The receiving position of the basket 9 is changed by the raised portion 9^b of the cam 51_a, which will cause engagement of the clutch mechanism for connecting the arm 35 to the arms 15' which are associated with the basket 9. This will bodily lift the basket 9 and cause it to discharge its contents into the compartment 20L, Fig. 4, of the basket 20. As indicated by the pair of lines G^a and G²⁰, when the basket 9 is in discharging position, the basket 20 is in receiving position. It being remembered that the rod 34 is in its right hand position, as shown in Fig. 2, it will be seen that the baskets are raised to their discharging position only during movement of the rod 34 in the right hand direction. When the contents of the baskets have been discharged, the arms 35 are returned to their stationary position upon left-hand movement of the rod 34. By the time the shaft 14 rests upon the supports 42 the cam 51_a will have caused disengagement of its clutch mechanism and thereby release the rocking arm 35' from the lifting arms 15'. With the loading basket 9 again in its receiving position, the operator will fill the compartment 9R, during which time the basket 20 will have been rocked from its receiving to its intermediate position and back again a number of times, as indicated by that portion of the line 20_b between the 30 and 210 degree lines. After this predetermined number of rockings of the basket 20, the loading basket 9 will again be raised to discharge the contents of the compartment 9R into the compartment 20R at a time when the basket 20 is in its receiving position. This is caused by engagement of the clutch mechanism associated with the rocking arm 35 and lifting arms 15 being thrown into engagement by the second raised cam portion 9 of the cam 51_a. The loading basket 9 is thereafter again lowered to its receiving position and the operator again fills the compartment 9L. During this time, however, the basket 20 is rocked, say, one minute longer, after which the cam 51₂₀ will cause engagement of the clutch mechanism associated with the basket 20. This position of the cam is indicated at 20_a in Fig. 23 and the basket is indicated as being in its discharge position by the line 20_b touching the line D. The articles which were in compartment 20L at the time of discharge from the basket 20 will have been subjected to the solution within the tank 4 twice as long as the articles in the compartment 20R. When the basket 20 is in its discharge position the basket 21 is in its receiving position, as indicated by the line 21_b touching the line D. The basket 21 is then rocked a number of times until its cam 51₂₁ causes engagement of its clutch mechanism to connect its rocking arm 35 and lifting arms 15 and thereby raise the basket 21 to

discharging position. The basket 22 at this time is in receiving position. This series of steps is carried on through the basket 23 during which time the series of steps is being repeated starting with the loading basket 9.

When the basket 23 is brought to its discharging position, baskets 24L and 24R are simultaneously brought to their receiving position. This is indicated by the line 23, 10 touching the discharge line D on the 150° line wherein the lines 24R_b and 24L_b are both touching the receiving line R. To compensate for the unequal time during which the articles in the compartments 20L and 20R 15 are subjected to the solution in the tank 4, the basket 24L will be rocked only one minute while the basket 24R will be rocked two minutes before they are alternately brought to their discharging position. This is indicated by the basket line 24L_b moving from the receiving and intermediate positions between the zero and 270 degree line, when the cam 83 then causes engagement of the clutch mechanism 85 thereby to raise the basket 24L 20 to its discharging position. The contents of the basket 24L will be discharged by the aid of the deflecting member 28' into the single compartment basket 105 of the second section. Raising of the basket 24L is effected by having the cam 95 move the arm 89 as shown in Figs. 13 to 15. The shaft 60 which is being continuously oscillated by the arm 67', Fig. 13, will be positively connected to the sleeve 64 upon engagement of the clutch mechanism 85. 25 Upon movement of the arm 67' in the right hand direction, the lifting arms 65 and 66 will be raised, thereby carrying the basket upwardly. The basket is of course, as previously stated, rotated about the axis of the basket shaft 68 due to the pivotal connection 69 being offset from the axis of the shaft 60. Upon the next rearward movement of the arm 67' the basket 24L will be returned to its intermediate position after which the cam 40 95 will release the clutch mechanism 85. During this time the basket 24R has been continuously rocking in the solution contained in the tank 4. This continuous rocking is indicated by that portion of line 24R_b between the 120° and 360° lines, and that portion between the zero and 60° lines. The cam 83, after this series of rockings, will move the arm 77 to engage the clutch 75 and thereby cause the lifting arms 65 and 76 which are 45 associated with the sleeve 63 to raise the basket 24R. This discharging position is of course obtained during movement of the arm 67 in a right hand direction and after the arm 67 moves to its left hand position the 50 clutch mechanism will be released.

Thus, within a two-minute interval both transferring baskets have alternately discharged their contents into the basket 105. Accordingly, to permit the basket 105 to handle separately the contents of both transfer-

ring baskets, it is necessary that the basket 105 discharge twice as often as either one of the transferring baskets. This is accomplished by driving the cam shaft 131 of the second section twice as fast as the cam section 52 as through the sprockets 207 and 208. When the basket 105 receives the contents from the basket 24L, the basket 105 is rocked and then discharges into the basket 106 which, it will be remembered, is never rocked but only moved between receiving and discharging positions. The tank disposed below the basket 106 might contain a solution with which it is only desired to allow the articles to come momentarily in contact. The discharge of the contents from basket 105, which receives the same from the basket 24L, is represented by the line 105_b touching the discharge line D at the lower 60° line. During the discharge position of the basket 105 the basket 106 is represented as being in a receiving position in that the line 106_b coincides with the receiving line R at the lower 60° line. The discharging position of the basket 106 is indicated by the touching of the line 106_b with the line D at the lower 180° line. The discharge of the contents from the basket 24R into the basket 105 is indicated at the 180° line while the discharge of the basket 105 of its contents is indicated at the upper 60° line. During this latter discharge of basket 105 the basket 106 is indicated as being in a receiving position, but shortly after receiving it will, as indicated at the upper 180° line, discharge. The pair of lines G¹⁰⁶ are shown in duplicate, one of which is slightly displaced from the other. This displacement is effected by rotation of the cam 159 relative to the cam shaft, this adjustment feature being accomplished by the mechanism disclosed in Figs. 19 to 22, the operation of which has been previously described. It will be seen that if the cam 159 is rotated it will cause the basket 106 to discharge its contents which have been in the basket 106 and only during 60° of cam rotation, this being indicated by the difference between the 60° and 120° lines. In the first case the length of time which the basket 106 contains the articles is indicated by the difference between the 60 and 180 degree lines. The actual time interval is indicated in seconds at the right hand end of Fig. 23. The basket 107, which is operated by the mechanism for actuating the basket 106, will receive the contents in the basket 106. The basket 107 will then rock rapidly a number of times before discharging. This series of rapid rockings is clearly indicated by the line 107_b. After a predetermined number of rockings the basket 107 will discharge into the basket 108 which is actuated by the mechanism for actuating the basket 105. The number of rockings in this case is smaller than in the case of the basket 107.

The mode of operation of the linkages in-

cluding links and arms 114, 119, 121 and 136 for actuating baskets 105—108 is as follows: Assuming the cams 130, 159, 169 and 142 to have their proper timed relation as indicated in Fig. 23, upon rotation of the crank arm 219 as by rotation of the shaft 216, gears 215, 201, shaft 199, work gear 70, worm 194, and driving pulley 195, the link 122 will cause oscillation of the arms 119 and 117. As long as the cam 130 keeps the clutch mechanism associated with the shaft 111 out of engagement, the links 113 and 114 will cause rocking of the shaft 109 by members 113 and 114 and consequently of the basket 105. As soon as the clutch mechanism is thrown into engagement, the arm 119 will be connected to the lifting arm 110 and accordingly raise the basket 105 to its dotted line position as shown in Fig. 16. During oscillation of the arm 119, the rod 121 will be reciprocated and as shown in Fig. 17 will cause oscillation of the arms 136 and 138. While the clutch mechanism associated with the shaft 137 remains out of engagement, the link 114 and arm 113 will cause oscillation of the shaft 139 and accordingly rock the basket 108. However when the cam 142 causes the clutch mechanism to become operative, the lifting arms 140 will be connected to the arm 136, and accordingly during movement of the arm 136 in counterclockwise direction the lifting arms will move upwardly carrying the basket 108 therewith and by cooperation of the link 114 and arm 113, as previously described, the basket will be rotated about the axis of the shaft 139 to its discharging position.

The baskets 106 and 107 are actuated by rotation of the crank arm 213 which is driven at a faster rate of speed than crank arm 113. It is by this faster rotation that the basket 107 is made to rock fast in accordance with the line 107_b. This crank rotation is effected by the gears 201, 212 and 211 driven from the driving pulley 195. Upon rotation of the crank arm 213 the link 157 will cause oscillation of the arms 155 and 156 and accordingly reciprocation of the rod 158 and oscillation of the arm 166, which is associated with the basket 107. As long as the clutch mechanism associated with the shaft 167 is inoperative, the basket 107 will merely be rocked but when the clutch mechanism is made operative by the cam plate 169 the lifting arms 176 will be connected to the arm 166 whereupon the basket 107 will be raised to its discharging position. It will be noted however, that the clutch mechanism must be made operative when the arm 166 is in its right hand position. The basket 106 is not rocked but merely moved from receiving to discharging position, this being effected by the cam plate 159 causing the clutch mechanism associated with the shaft 152 to be operative. When the clutch is operative and the arm 155 is in its left hand position, the

lifting arms 151 and arm 155 will be connected. During movement of the arm 155 in a right hand direction, the arms 151 will move upwardly and carry the basket 106 to its discharging position. Rotation of the basket 106 about the axis of the shaft 150 is effected by the arm 165 and link 163 which is connected to the stationary support 162.

The articles when discharged from the last basket 108 are received in suitable containers or baskets, which pass through a drier 280. This drier comprises a substantially rectangular housing 281 having its opposite ends open to permit a suitable conveying mechanism to pass entirely through the drier. This conveyor comprises a pair of chains 282 carried by suitable sprockets 283 and 284, which are suitably journaled upon longitudinal side members 285 and by the end of the frame members 100. Disposed transversely of and supported by the chains 282 are series of longitudinally spaced receptacles 286, each having an open top. The chains 282 are so timed that one of the receptacles 286 will always be immediately below the last basket 108 when the latter is in discharging position. The chain 282 runs in a clockwise direction so that the articles will be discharged at the right-hand end of the drier, as shown in Fig. 7. By having the separate receptacles 286 the various articles such as spoons, knives and forks will be kept separately.

The mechanism for driving the chains 282 comprises a pair of beveled gears, one of which is fixed to the end of the cam shaft 181, and the other upon a shaft which carries a sprocket 287, the beveled gears being disposed within a housing 288. A sprocket 289 fixed to shaft 290 which carries the sprockets 283, is driven by suitable chain passing around the sprockets 287 and 289. It will, of course, be understood that the drier may be of any suitable type whereby the articles may be continuously moved from their initial cleaning operation to their final disposition.

I claim:

1. A machine of the class described comprising a basket, means for rocking the same a predetermined period of time, means for automatically imparting additional movement to said basket and power operating means for actuating both of said means.

2. A machine of the class described comprising a basket, means for moving the same from a receiving position to a reciprocal rocking position, and means for moving said basket to a discharging position.

3. A machine of the class described comprising a basket, means for rocking the same about an axis, and means for bodily moving said basket in a circular path about an axis offset from the rocking axis.

4. A machine of the class described comprising a basket, means for supporting the

- same, means for reciprocating the same about an axis, means for moving the same about a second axis and a connecting means for moving said basket about said axes.
5. A machine of the class described comprising a basket, supporting means therefor including a reciprocating pivotal connection between said basket and supporting means, means for pivotally supporting said supporting means and a connecting means for actuating said basket and said supporting means. 70
6. A machine of the class described comprising a basket, means for imparting a series of substantially identical rocking movements thereto, and means for automatically imparting additional movement thereto after a predetermined number of movements in said series. 75
7. A machine of the class described comprising a receptacle, a supporting arm, means for pivotally supporting said receptacle on said arm, means for pivotally supporting said arm, means for moving said receptacle about its pivot with a reciprocating movement including a crank arm and actuating link and a connecting means between said arm supporting means and said means for moving said receptacle about its pivot. 80
8. A machine of the class described comprising a receptacle, means for supporting and actuating the same including a pivotally mounted arm having reciprocating pivotal supporting connection with said receptacle, means for controlling the movement of said receptacle including a member movable relative to said supporting means and connected mechanism for actuating said arm and said receptacle. 85
9. A machine of the class described comprising an arm, a shaft for pivotally supporting the same, a receptacle movably supported by said arm, means for actuating said receptacle, including a movable member carried by said shaft, and means for operatively connecting said member to said receptacle. 90
10. A machine of the class described comprising a supporting arm, a shaft for pivotally supporting the same, a receptacle pivotally supported by said arm, and means for actuating said receptacle including an actuating member carried by said shaft and a pair of co-operating members operatively connecting said actuating member and receptacle. 95
11. A machine of the class described comprising a supporting arm, means for pivotally supporting the same, a receptacle pivotally supported by said arm, an actuating member associated with said pivotal supporting means, a pair of cooperating members operatively connecting said actuating member and receptacle, and means for connecting said actuating member and supporting arm. 100
12. A machine of the class described comprising a receptacle, means for supporting the same, actuating means for rocking said receptacle relative to said supporting means, and means for connecting said supporting means and said actuating means thereby to move said supporting means to position the receptacle for discharge of material. 105
13. A machine of the class described comprising a receptacle, means for imparting predetermined rocking movement thereto, and means for imparting additional movement thereto, both of said means including a common actuating element. 110
14. A machine of the class described comprising a receptacle, means for imparting predetermined movement thereto, means for imparting additional movement thereto including clutch mechanism, and means for actuating said clutch automatically in accordance with the first predetermined receptacle movements. 115
15. A machine of the class described comprising a receptacle, means for moving the same between receiving and intermediate positions, and means for automatically moving said receptacle to a discharging position after a predetermined number of said first movements. 120
16. A machine of the class described comprising a receptacle, means for moving the same from a receiving to a reciprocating rocking position, and means for moving said receptacle to a discharging position from said reciprocating rocking position. 125
17. A machine of the class described comprising a receptacle, means for pivotally supporting the same in a receiving position, and means for moving the supporting means to a discharging position, both of said means including a common supporting shaft and a controlling link. 130
18. A machine of the class described comprising a receptacle, means for pivotally supporting the same in a receiving position, means for moving the supporting means to a discharging position, both of said means including a common supporting shaft and a controlling link, and means for pivotally supporting said link about a stationary axis. 135
19. A machine of the class described comprising a pair of cooperating receptacles, means for imparting a predetermined initial movement to each of the same, and means for bringing said receptacles into cooperative discharging and receiving positions. 140
20. A machine of the class described comprising a pair of cooperating receptacles, means for imparting predetermined initial movements to each of the same, and means for bringing said receptacles into cooperative discharging and receiving positions, including means for imparting additional movement to one of said receptacles while the other receptacle is in its initial predetermined movement. 145
21. A machine of the class described comprising a pair of cooperating receptacles, 150

- means for imparting a predetermined initial movement to each of the same, means for bringing said receptacles into cooperative discharging and receiving positions, including means for imparting additional movement to one of said receptacles while the other receptacle is in its initial predetermined movement, and means for permitting said first receptacle to continue its initial movement 10 after said cooperative relation.
22. A machine of the class described comprising a pair of cooperating receptacles, means for imparting a predetermined initial movement to each of the same, means for bringing said receptacles into cooperative discharging and receiving positions, including means for imparting additional movement to one of said receptacles while the other receptacle is in its initial predetermined movement, and means for thereafter imparting additional movement to said second receptacle. 15
23. A machine of the class described comprising a pair of baskets, means causing the first basket to rock to and fro and thereafter discharge into the second basket, and means causing the second basket to rock to and fro and thereafter discharge its contents received from the first basket. 20
24. A machine of the class described comprising a pair of baskets, means for pivotally supporting said baskets, and means for bodily lifting one of said baskets with its supporting means so as to discharge its contents into the other basket. 25
25. A machine of the class described comprising a pair of baskets, means for rocking said baskets, and means for bodily lifting one of said baskets so as to discharge its contents into the other basket. 30
26. A machine of the class described comprising a pair of baskets, a tank within which the same may be disposed, means for agitating said baskets while disposed in said tanks, and means for lifting one of said baskets from said tank to discharge its contents into the second basket. 35
27. A machine of the class described comprising a plurality of tanks, each tank having a rocking basket, means for discharging the contents of one of said baskets into another basket, and means whereby during this discharge the first basket will be free from a liquid in its cooperating tank. 40
28. A machine of the class described comprising a plurality of baskets, means whereby a number of the same may be moved simultaneously to a receiving position, and means whereby one of said baskets may be moved so as to discharge into one of said baskets which is in a receiving position. 45
29. A machine of the class described comprising a plurality of baskets, means for rocking the same to and fro in a fixed position, including an actuating arm associated 50
- with each of said baskets and a reciprocable member connected to each of said actuating arms.
30. A machine of the class described comprising a plurality of baskets, means for agitating the same, and means for periodically and automatically moving the same to a discharging position, both of said means including a common actuating means. 55
31. A machine of the class described comprising a plurality of baskets, means for simultaneously rocking the same, and means for periodically lifting one of the same including a clutch mechanism and a cam mechanism for controlling said clutch mechanism. 60
32. A machine of the class described comprising a pair of baskets, means for rocking one of said baskets while the other remains stationary, and means for moving the latter basket to a discharging position. 65
33. A machine of the class described comprising a pair of baskets, means for holding one of same in a receiving position, means for moving the other between two predetermined positions, and means for periodically bodily lifting said held basket to permit material therein to discharge into the moving basket when the latter is in one of its positions. 70
34. A machine of the class described comprising a receiving basket normally remaining in a receiving position and a basket disposed on one side thereof, means for rocking said latter basket and for moving the same to a position for discharging its contents into the receiving basket, and means for immediately thereafter moving said receiving basket to a discharging position. 75
35. A machine of the class described comprising a plurality of baskets, means for discharging said baskets, and means for controlling certain of said baskets whereby one will hold its contents for a longer period than another basket. 80
36. A machine of the class described comprising several baskets, means for discharging the contents from one basket into an intermediate basket, means for rocking said intermediate basket, and means for thereafter quickly discharging the contents from said intermediate basket into another basket. 85
37. A machine of the class described comprising a plurality of tanks, means for supporting material in each of said tanks, means for passing material from one supporting means to another, and means for controlling said supporting means whereby the material is disposed in one tank a greater length of time than in another tank. 90
38. A machine of the class described comprising a tank and a receptacle disposed therein, means for moving said receptacle to a discharging position after receiving a load, and means for varying the length of time that said receptacle remains in said tank be- 95

fore being moved to its discharging position.

39. A machine of the class described comprising a tank and a basket disposable therein, means for moving said basket to a discharging position after receiving a load, and

5 means for varying the length of time between the receiving and discharging of a load by said basket.

40. A machine of the class described com-

10 prising a tank and a basket disposable therein, means for moving said basket to a discharging position after receiving a load, and means for varying the length of time between the receiving and discharging of a load by

15 said basket, said varying means including a cam and a cooperating follower member, and means for effecting relative movement between said cam and follower.

41. A machine of the class described com-

20 prising a tank and a basket disposable therein, means for moving said basket to a discharging position after receiving a load including clutch mechanism and a clutch-controlling means, and means for varying the

25 length of time between receiving and discharging a load by said basket, said varying means including mechanism for advancing or retarding the clutch-controlling mechanism.

42. A machine of the class described com-

30 prising a basket, means for moving said basket to a discharging position after receiving a load including a driven member, means for varying the length of time between the receiving and discharging of a load by said

35 basket, and means for preventing operation of said varying means while said driven member is operative.

43. A machine of the class described comprising a basket, means for moving said basket to a plurality of positions, including a

40 belt driven pulley, and means for varying the length of time between movement of said basket to its plurality of positions, and means for controlling the operation of said

45 varying means in accordance with the position of the driving belt relative to said pulley.

44. A machine of the class described com-

50 prising a plurality of pairs of baskets, means whereby certain of the same discharge into others, and actuating means therefor includ-

55 ing means for separately actuating said pairs of baskets.

45. A machine of the class described comprising a pair of baskets and a basket inter-

55 mediate thereof, means connecting said pair of baskets, actuating means for said connecting means and a separate actuating means for said intermediate basket, and means whereby said pair of baskets discharge into the inter-

60 mediate basket.

46. A machine of the class described comprising a plurality of pairs of baskets, means for moving said baskets from receiving to

65 discharging positions thereby to allow the contents of one basket to be discharged into

another basket, and means whereby the length of time for allowing one basket to hold its contents is greater than the time allowed by another basket.

47. A machine of the class described com-

70 prising a plurality of baskets, means for moving the same from receiving to discharging positions thereby to allow the contents of one basket to discharge into another basket,

75 means for additionally moving two of said baskets prior to being moved to their discharging position, and means for moving a basket intermediate said two baskets at a greater rate than the movement of said two baskets.

48. A machine of the class described comprising a plurality of baskets, means for moving the same from receiving to discharging

80 positions thereby to allow the contents of one basket to discharge into another basket, means for additionally moving two of said baskets prior to being moved to their discharging position, and means for moving a basket intermediate said two baskets at a greater rate than the movement of said two

85 baskets, and means for moving still another basket intermediate said two baskets only from a receiving position to a discharging position.

49. A machine of the class described com-

90 prising a pair of cooperating baskets one of which is adapted to discharge into the other, means for moving said baskets from a receiving to a discharging position, and means for imparting additional movement to one of said

95 baskets at a given rate and means for imparting additional movement to the other basket at a greater rate.

50. A machine of the class described com-

100 prising a pair of cooperating baskets one of which is adapted to discharge into the other, means for moving said baskets from a receiving to a discharging position, means for im-

105 parting additional movement to one of said baskets at a given rate and means for im-

110 parting additional movement to the other basket at a greater rate, and means whereby said fast-moving basket is adapted to be in a dis-

115 charging position when said slower moving basket is in a receiving position.

51. A machine of the class described com-

120 prising a pair of baskets, means for moving the same from a receiving to a discharging position whereby one may discharge into the other, actuating means for said baskets in-

125 cluding elements for connecting said baskets;

and means whereby said actuating means is adapted to impart additional movement to only one of said baskets.

52. A machine of the class described com-

130 prising a plurality of baskets disposed later-

ally of each other, and means for alternately moving the same to a discharging position.

53. A machine of the class described com-

135 prising a plurality of baskets disposed later-

- ally of a center line through the machine, means for moving said baskets to a discharging position, and means whereby one of said baskets holds its load a greater length of time than the other basket.
54. A machine of the class described comprising transferring baskets, means whereby the same simultaneously receive their respective loads, and means for moving one of 10 said baskets to its discharging position a substantial period before the other basket is moved to its discharging position.
55. A machine of the class described comprising transferring baskets, means for pivotally supporting the same, means for rocking said baskets including a common element, and means for moving one of said baskets to its discharging position prior to movement of the other basket to its discharging position.
56. A machine of the class described comprising transferring baskets, means for moving said baskets to a discharging position, and means whereby said baskets discharge to 20 substantially the same area.
57. A machine of the class described comprising transferring baskets, means for moving the same to a discharging position including a clutch mechanism associated with each 30 of said baskets, and means for alternately causing said clutches to be operative including cam mechanism.
58. A machine of the class described comprising a loading basket and a receiving basket 35 cooperating therewith, means for moving said receiving basket from a receiving to an intermediate position a number of times in succession and actuating means for moving said loading basket to a discharging position when said receiving basket is in its receiving 40 position, said actuating means being operative a plurality of times during a continuous series of movements of said receiving basket from its receiving to its intermediate position.
59. A machine of the class described comprising a loading basket, a receiving basket 45 adapted to cooperate therewith, each of said baskets having compartments, means for moving said receiving basket from a receiving to an intermediate position a plurality of times in succession, means whereby one compartment of the loading basket when filled will discharge its contents into one compartment 50 of the receiving basket during said movements of the latter, and means whereby another compartment of the loading basket may discharge its contents into another compartment of the second basket at a time different 60 from the other loading operation.
60. A machine of the class described comprising a loading basket, a receiving basket 65 adapted to cooperate therewith, each of said baskets having a plurality of compartments, means for moving said receiving basket from 70 a receiving to an intermediate position a plurality of times in succession, means whereby one compartment of the loading basket when filled will discharge its contents into one compartment of the second basket during said movements of the latter, and means whereby another compartment of the loading basket may discharge its contents into another compartment of the second basket at a time different 75 from the other loading operation, and means for simultaneously discharging the contents from both compartments of the receiving basket.
61. A machine of the class described comprising a tank, means for supporting articles 80 in a solution contained within said tank, means for loading articles onto said supporting means at different intervals of time, and means for compensating for this time difference whereby the articles will be subjected to the solution the same length of time.
62. A machine of the class described comprising a tank, a plurality of receptacles disposed therein, means permitting said receptacles to receive at different periods of time 85 articles which are to be subjected to a solution in the tank, means for discharging said articles from said receptacles, and means for compensating for this difference in time of loading whereby said articles are subjected to the same length of time to the solution in said tank.
63. A machine of the class described comprising a tank and a plurality of baskets disposed in said tank on parallel axes, each of 90 said baskets having a pair of compartments, means for loading the compartments of one basket at different intervals, means for simultaneously discharging the load from said latter basket to its adjacent basket, and means for compensating for the different loading intervals whereby both loads will be subjected to the solution in said tank substantially equal lengths of time.
64. A machine of the class described comprising first and second sections of baskets, means whereby said baskets discharge successively from one to another thereby to feed material in one direction, tanks associated with the baskets of each section, and means for actuating the baskets of one section at a greater rate of speed than the baskets of the other section.
65. A machine of the class described comprising first and second sections of baskets, 110 means whereby said baskets discharge successively from one to another thereby to feed material in one direction through said machine, tanks associated with the baskets of each section, and means for actuating the baskets of one section at a greater rate of speed than the baskets of the other section.
66. A machine of the class described comprising a plurality of basket compartments 115 disposed laterally of each other, means for actuating the basket compartments of one section at a greater rate of speed than the basket compartments of the other section, and means for feeding material into the basket compartments of the section having the greater rate of speed.

66. A machine of the class described comprising tanks, means for feeding articles in parallel through certain of said tanks, and means for changing said parallel feed into 5 a single feed through certain of the other of said tanks.

67. A machine of the class described comprising tanks, means for feeding articles in parallel through a solution contained in certain of said tanks, and means for feeding said 10 articles in a single line through the solution in certain of the other tanks and at a greater rate of speed than when said articles are fed in parallel.

68. A machine of the class described comprising a pair of sections each having baskets, means for discharging material from one basket to another whereby said material is fed in one direction through said sections, 15 means for imparting a reciprocating rocking motion to some of said baskets and actuated, means for the baskets of said sections disposed substantially at the adjacent ends 20 of said sections.
